Application December 24, 1940, Serial No. 371,496

6 Claims. (Cl. 202—262)

This invention relates to improvements in apparatus suitable for coking of hydrocarbons.

In our copending application, Serial No. 274,092, filed May 17, 1939, now Patent No. 2,226,501, patented December 24, 1940, of which the present application is a continuation-in-part, we have described an apparatus which is particularly adaptable for the coking of hydrocarbon materials derived from the cracking of petroleum. The main feature of such apparatus is the provision of a removable liner of flexible material for a coking chamber. The coking reaction takes place entirely within the liner so that, during the reaction, the hydrocarbons undergoing coking do not come into contact with the wall of the coking chamber. The resulting coke mass may be easily removed intact from the chamber at the end of the coking operation and corrosion and erosion of the coking chamber are substantially avoided. The liner is preferably spaced from the chamber wall so that it may be readily removed from the chamber. After removal of the liner containing the resulting coke mass, the liner, being flexible, may be conveniently stripped therefrom when desired, and the coke may be obtained substantially in one piece with a minimum production of fines.

The principal object of our present invention is to provide an improved removable liner for a coking chamber, which liner can be easily removed from the coke mass without the destruction of either the liner or the coke mass.

Another object of our invention is to construct the removable liner from a plurality of similar, interchangeable sections so that the liner may be more easily disengaged from the resulting coke.

Still another object of our invention is to construct the improved removable liner in such a manner that it can be used and reused a great number of times without substantial deterioration.

Further objects and advantages of our invention will appear from the following disclosure of a preferred form of embodiment thereof taken in connection with the attached drawing, illustrative thereof, in which:

Fig. 1 is a vertical cross-section taken through a coking chamber provided with our improved liner, which is shown partly broken away and partly in section;

Fig. 2 is a horizontal cross-section of our improved liner taken substantially along the line 2—2 of Fig. 1;

Figs. 3 and 4 are details of our improved liner; and

Fig. 5 is a vertical section of a modified detail. In accordance with our invention, the improved liner is constructed of a plurality of sections which are so fabricated that they may be interlocked to form a substantially leak-proof structure. Each section is provided with means whereby, after the coking operation has been completed and the liner containing the coke mass has been removed from the coking chamber, it can be quickly and easily disengaged from the coke mass. The sections are also constructed so as to substantially prevent the formation of coke about the sectional disengaging means.

As described in our copending application, the coking apparatus includes an open-ended pressure chamber, generally indicated at 10, provided with a cover 12. Both of these sections 20 may conveniently have flanges 14 and 16, respectively, by means of which they may be assembled as by bolts 18. Chamber 10 may also be provided with a manhole 20 so that the interior thereof may be inspected upon occasion 25 for corrosion and other purposes. Preferably a cover 21, normally fastened to chamber 10 as by bolts 22, is provided for manhole 20.

Chamber 10 is also provided with a liner, generally indicated at 24, which may conveniently 30 have an outwardly projecting flange 25 for support thereof within the chamber. During assembly of the apparatus, it will be appreciated that suitable gasket material will be placed between the respective flanges of chamber 10, liner 24, and cover 12 to insure a tight seal. Liner 24 preferably has substantially the same cross-sectional shape as chamber 10 but a somewhat smaller cross-sectional area so that it is thereby spaced from the wall of chamber 10. Provision 35 is thus made so that the liner can be easily inserted and removed despite any substantial buckling or expansion thereof.

During the coking operation, hydrocarbon material to be coked is introduced under suitable 45 temperature and pressure conditions into chamber 10 through opening 28 in cover 12. This material undergoes coking entirely within the zone defined by liner 24. The vapors from the coking reaction pass upwardly over the top edge 50 30 of liner 24 and then downwardly through the annular space 32 between the liner and the chamber and out through the outlet 34. Passage of the hydrocarbon vapors through the coking chamber in this manner makes possible 55 the maintenance of the contents of the cham-

ber at a more even coking temperature and consequently results in a higher conversion of the hydrocarbons being coked and the formation of a better coke.

According to our present invention, we have provided an improved construction for liner 24. In such construction a plurality of preferably similar sections 36, four of which are shown in the drawing, are suitably interlocked in the shape of the liner. Alternate sections may be provided with overlying lips 37 and underlying lips 38, respectively, as shown, or any other suitable means may be employed. As also shown, each section may have flanges 40 by means of which the sections may be held together as by bolts 41. A metal gasket 42 or the like is preferably inserted at each sectional joint to insure against leakage. If desired, the sections may be held together by horizontal metal straps or similar devices in lieu of or in addition to the flange bolts 41.

The shape of each section will be such that, when all are assembled, the resulting liner will preferably have a cross-section similar to that of the chamber into which it is inserted. Although the sections shown in the drawing are arcuate in shape, any other form which may be found desirable may also be used. It will be noted that the sections as shown extend the whole vertical length of the liner. It is also within the scope of our invention, however, to utilize a plurality of sections which extend only part of the ultimate height of the liner; in such case, the sections may be joined both vertically and horizontally in the manner heretofore described.

The lower edge of each section shown in the drawing is preferably provided with an outwardly extending flange for support of the assembled liner within the chamber as in the apparatus described in our copending application. These sections are so formed that, when assembled, the liner has a cross-sectional area somewhat smaller than that of the chamber.

Each section is provided with a plurality of pressure-applying bolts 44, the purpose of which will be more fully described hereinafter. Preferably these pressure bolts are arranged in vertical columns and are suitably spaced so that pressure can be equally applied to every portion of the section. Details of the preferred construction of the pressure bolts are shown in Fig. 3. It will be noted that each of these pressure bolts is provided with a head 46 or the like at one end thereof so that it may be slipped into a corresponding keyhole or bayonet slot 48 in a pressure strip 50. Pressure strips 50 are used as a base against which the pressure from pressure bolts 44 may be exerted. A pressure strip 50 is provided for each of the vertical rows of pressure bolts as shown. Pressure strips 50 may be employed in either a vertical or a horizontal position; the vertical position is preferred, however, since the constructional and operational disadvantages of the horizontal position are not present.

For added strength, liner 24 may be provided with a plurality of bosses 52 so that the pressure bolts 44 can be better accommodated. Preferably the head portion 46 of each pressure bolt 44 is somewhat smaller in cross-sectional area than the rest of the bolt so that the entire bolt may be directly inserted through boss 52; any other construction which may be found desirable may be used, however. Although we prefer to use the head and keyhole construction described,

any other system which can effectively accomplish the same purpose may also be used.

When liner 24 is prepared for use, the several sections thereof are bolted or strapped together, 5 and pressure bolts 44 are inserted in the keyhole slots of the corresponding pressure strips 50. Pressure strips 50 are preferably so constructed that, when the assembled liner is placed in its vertical operating position, the narrow portion of 10 the keyways or keyhole slots 48 is uppermost and the pressure bolts 44 are thus locked in position. When the liner has been assembled, the pressure strips 44 are flush with the coke-forming surface of the various sections 36, as indicated in Fig. 15 2. The assembled liner is then inserted into coking chamber 10, cover 12 is bolted on, and hydrocarbon materials to be coked are introduced into chamber 10 through opening 28. Prior to the 20 insertion of the liner, however, each of the pressure bolts 44 is preferably covered with a suitable material such as asbestos mud or clay as indicated at 54 in order to prevent coking of the threads of the pressure bolts or other possible damage thereto by the hydrocarbon vapors as 25 they pass through annular space 32.

It should also be noted that the construction 30 of the pressure strips 50 is preferably such that the deposition or formation of coke about the keyhole slots 48 and keyed ends 46 of pressure bolts 44 is substantially prevented. Since the keyhole slots preferably extend only partially through the pressure strips and since the pressure strips are maintained flush with their respective sections, the possibility of any coke formation in the keyhole slots or about the inner 35 end of the pressure bolts is practically negligible, and the difficulty in removing the sections, which would otherwise be encountered, is materially avoided. If desired, depressions or grooves may 40 be made in the coke-forming surface of each section so that the respective pressure strips may be inserted therein either wholly or partially; in such case, further protection against coke deposition in the keyhole slots is obtained.

After the coking operation has been completed, 45 cover 12 is removed, and liner 24 containing the resulting coke mass is withdrawn from chamber 10. The liner and the coke mass may then be allowed to cool, if desired, and the liner may be 50 stripped from the coke mass when it is convenient to do so.

When the liner is to be removed from the coke, 55 pressure bolts 44 are driven down as far as practicable. Usually the sections will adhere to the coke mass; if the sections are tapped with an air hammer or the like, however, they may be thus loosened from the coke mass. Since the sections have been put under a strain after the pressure bolts have been driven down, they may be easily 60 disengaged from the coke mass in this manner. The pressure strips 50 ordinarily adhere to the coke mass and are not separated therefrom when the sections 36 are separated from the coke. In such event, pressure bolts 44 are disengaged from 65 their respective keyhole slots in the pressure strips 50, and the corresponding section is slipped off the pressure strips and is removed from the coke mass. By means of hammering, chipping, or the like, the pressure strips 50 may then be 70 separated from the coke mass. The relative positions of the liner with respect to the coke mass are shown in Fig. 3, in which the coke mass is indicated at 56. The several sections may then be reassembled and prepared for reuse in further 75 coking operations.

A modified manner of applying the pressure to the transverse pressure strips is shown in Fig. 5, in which the bolts 144, mounted in bosses 52 on the liner, are adapted to engage the pressure plate 150 to force the liner away from the coke mass 56. In this construction, there is no possibility of interference by the coke, the plates 150 being initially supported as by temporary dowels 160.

The sections 36 should be designed light enough so that they may be pulled together to compensate for longitudinal warping and the like after use. At the same time, the sections should be sufficiently heavy and strong so that, when the pressure bolts are driven down, the resulting strain set up in the sections will not tear or otherwise rupture them. When compared with the flexible (erroneously called frangible) liner described in our copending application, the present composite liner is preferably somewhat heavier in gage, being approximately one-quarter inch thick for a forty foot shell of ten feet in diameter rather than 16 or 18 gage.

It will be apparent that we have provided an improved liner for a coking chamber whereby the coke mass formed within the liner may be readily obtained substantially intact. It is to be particularly noted that the principal features of our invention reside in the provision of a relatively thin sheet metal liner composed of a plurality of interlocking sections which can be separated from the resulting coke mass by means of appropriate adjustable pressure-applying devices or the like. The construction of the assembled liner is such that ample protection is afforded the movable parts against coke deposition and any other possible damage and the parts may be reused many times.

Although we have described a preferred form of embodiment of our invention, we are aware that modifications may be made thereto; therefore, only such limitations as appear in the claims appended hereinafter should be applied.

We claim:

1. A coking chamber of the class described, including an outer chamber, a plurality of sections adapted to form an internal chamber, means to hold said sections in assembled position, means to form a coke body within said sections, and means carried by said sections for separation of the coke formed within said internal chamber, said means including a plurality of pressure strips for each section and pressure-applying devices, and means in said pressure strips to receive and hold said pressure-applying devices.

2. A removable, composite liner for a coking chamber of the class described, which comprises a plurality of curved sections forming a chamber extending throughout substantially the entire length of the coking chamber, means to hold said sections in assembled position, a plurality of pressure-applying bolts carried by said sections, a plurality of pressure strips for each section, said pressure strips being substantially

flush with the inner surface of said sections and forming a base for the pressure-applying bolts whereby, on adjustment of said bolts, said pressure strips will dislodge the coke from the sections.

3. A removable, sectional liner for a coking chamber of the class described, which comprises a plurality of sections extending substantially the entire length of the liner, means to hold said sections in assembled position, a plurality of pressure-applying bolts carried by each section, a plurality of pressure strips for each section, said pressure strips forming a base for the pressure-applying bolts, and means to hold said pressure strips in position during coke formation.

4. A removable, sectional liner for a coking chamber of the class described, which comprises a plurality of sections extending substantially the entire length of the liner, means to hold said sections in assembled position, a plurality of pressure-applying bolts carried by each section, a plurality of pressure strips for each section, said pressure strips forming a base for the pressure-applying bolts, said pressure strips having a series of slots engaging the respective pressure-applying bolts to hold the pressure strips in position during coke formation.

5. A removable, sectional liner for a coking chamber of the class described, which comprises a plurality of sections extending substantially the entire length of the liner, means to hold said sections in assembled position, a plurality of pressure-applying bolts carried by each section, a plurality of pressure strips for each section, said pressure strips forming a base for the pressure-applying bolts, and dowel means to hold said pressure strips in position during coke formation.

6. A removable, composite liner for a substantially circular coking chamber of the class described, which comprises a plurality of similar arcuate sections extending the vertical length of the liner, an outwardly extending flange along the lower edge of each section whereby the assembled liner is supported within said coking chamber and is spaced from the wall thereof, cooperating flanges along the vertical edges of each section, flange bolts passing through said flanges to hold said sections in assembled position, a plurality of vertical rows of pressure-applying bolts having one end thereof formed in the shape of a key and being carried by each section for separation thereof from coke formed within said liner, a plurality of vertical pressure strips for each section, said pressure strips being flush with the inner surface of said sections and forming a base for the pressure exerted by said vertical rows of pressure-applying bolts, and keyhole slots in said pressure strips to receive the keyed end of said pressure-applying bolts, said keyhole slots being so formed that the narrow portion thereof is uppermost whereby the sections are locked in position when the assembled liner is inserted in the coking chamber.

VALENTINE MEKKER.
